UNITED STATES PATENT OFFICE.

OWEN D. KINSEY, OF WAUWATOSA, WISCONSIN.

INTERNAL GRINDER.

Application filed June 20, 1925. Serial No. 38,413.

My invention has for its object the provision of what may be termed a portable precision grinder for grinding the internal cylindrical surfaces or bores of cylinders or valves, whereby the grinding operation may be speedy and accurately performed and an inappreciable amount of stock removed.

Another object of my invention is to provide a portable grinder whereby the operating medium or exhaust air will be directed toward the work and employed for blowing the ground material away from the grinding wheel to prevent "loading" of said wheel.

A further object of the invention is to provide means whereby the movable cylinders or spindles will be completely encased or housed; and wherein the driving gears may be easily controlled so as to provide a quick return of the mechanism to normal position.

Another object of the invention is to provide means, cooperating with the housing of the grinder, whereby an accurate and true centering of the grinder relative to the bore of the cylinder to be ground may be quickly and easily mechanically determined without the requirement of special skill.

The above enumerated advantages and objects of my invention will all be more fully comprehended and understood from the detailed description of the accompanying drawings, wherein:

Figure 1 is a longitudinal sectional view of my improved grinder shown applied to the end of a cylinder of which only a portion is shown in section.

Figure 2 is a detail sectional view of a portion of the inner cylinder and the rotor.

Figure 3 is a cross sectional view taken on the line 3-3 of Figure 1 looking in the direction of the arrows.

Figure 4 is a detail elevation and partial sectional view of my improved centering mechanism shown applied to the end of a cylinder of which only a portion is shown.

Figure 5 is a detail perspective view of one of the elements of the centering mechanism which is adapted to be secured to the cylinder to be ground and which receives the lower end of the housing of the grinder.

My invention relates to an internal grinder especially adapted for the grinding or truing of an internal cylindrical surface and particularly for use in connection with the truing or grinding of the internal surface of what are known as triple valves employed

on freight and passenger cars and forming part of the air-brake equipment; as well as for the grinding of what are known as distributing valves on locomotives.

These valves, in practice, are usually brass or bronze lined as shown at 10 in Figure 1 where a portion of the valve is shown at 11. In the operation of grinding, it is essential, as the first step in the operation, to provide means whereby the grinder will be properly centered relative to the axis of the valve or bore of the cylindrical device which is to be ground; this step or operation being accomplished by means of my improved composite centering mechanism which, in the particular exemplification, consists of an annular member 12 provided with a tapered or beveled opening 13; the member 12 being intended to be placed on the end of the valve or cylindrical member 11 as shown in Figures 1 and 4. The member 12, in the specific exemplification, is shown provided with locking members or cams 14, 14 rotatably secured on the upper surface of the annular member 12 so as to permit the cam portions or lips 15 thereof to overlap the opening as shown in Figure 5. The annular member 12 is also shown provided with a series of holes 16 arranged concentric with the tapered opening 13 and with a second series of openings 17 also arranged concentric with the tapered opening 13 (but at a shorter radius from the center) thus providing two radii to take care of triple valve flanges of different diameters. The holes 16 and 17 are intended to receive bolts 18, see Figure 4, which are provided at bottom with L-shaped heads 19 adapted to engage beneath the flange of the valve or cylindrical member 11. The centering mechanism also comprises a centering plug member 20 (see Figure 4) which is provided with an external taper corresponding with the taper of the opening 13 in the annular member 12; and this plug 20 is provided with a skirt portion 21 which is intended to enter the valve 11; the skirt portion being of slightly less external diameter than the internal diameter of the valve so as to permit of desired adjustment. The plug member 20 in turn is provided with a plug sleeve member 22, see Figure 4, the lower end whereof has an external bevel or cone formation terminating in a small lip as shown at 23 and carries a split or expansion ring 24. The up-

100
105
110

per end of the plug sleeve 22 (which extends through a plug member 20) is externally threaded to receive the plug sleeve nut 25. In practice, the annular member 12 is placed on the flange of the triple valve with the bolts 18 out of holding position; the plug member 20 is then inserted into annular member 12 and fastened thereon by any suitable locking device as for example the locking cams 14, 14. The plug sleeve nut or internally threaded cap 25 is then rotated and, by reason of its relation with the plug member 20, will cause the plug sleeve 22 to be drawn upwardly, thereby causing the cone surface 23 thereof to expand the ring 24 into firm gripping relation with the internal surface of the triple valve or other cylindrical device. This action causes the composite centering mechanism to be accurately adjusted or centered, at which time the L-head bolts 18 are turned into firm clamping relation with the flange of the triple valve 11. The annular member 12 is also provided with set-screws 26 which may now be turned or screwed inwardly so as to prevent any accidental shifting of the member 12; the set-screws also permitting of closer adjustment being made when found necessary. With the annular member 12 having thus firmly been secured to the flange of the triple valve, that is to say, the member 12 having been placed in absolute concentric relation with the axis of the triple valve, the plug sleeve-nut 25 is unscrewed, thereby releasing plug sleeve member 22 and its expansion ring 24. This permits the plug 20 with the sleeve 22 to be removed from the triple valve while the annular member 12 remains in place, concentric with the triple valve or other cylindrical element.

The grinder consists of a suitable housing 27; the base whereof is provided with a taper at 28 similar to the taper of plug 20 and therefore corresponding with the tapered orifice 13 of member 12. The tapered portion 28 of the casing 27 is inserted in the annular member 12, after the plug 20 of the centering mechanism has been removed, and is secured in place on the member 12, by the cam members 14, 14, or any other suitable clamping mechanism.

By reason of the member 12 of the centering mechanism having previously been centered, the grinder housing 27 is, therefore, held in true concentric relation with the bore of the triple valve. The base of the grinder housing or shell 27 is preferably shown provided with a number of openings at 29 to permit observation of the grinder-wheel 30 during grinding operation. The grinding-wheel 30, which is of well known type, is suitably and removably secured to the lower end of the turbine or rotor spindle 31 of the turbine or rotor 32. The rotor 32 comprises a cylinder provided with a plu-

rality of longitudinal slots, for example three in number, in each of which is secured or placed a loosely held movable blade member 33 which is free to move in and out radially to follow an eccentric circle. The 70 turbine or rotor 32 is mounted in a cylinder or tube 34 eccentrically, with one side in snug relation with the wall of the cylinder. This side of the cylinder is provided with an air passage 35 which communicates with the ports 36 leading into the interior of the cylinder or tubing, namely into the chamber in which the rotor 32 is located, see Figure 2; while the other end of the passage 35 communicates with the chamber 37 which receives the compressed air supply from pipe 38 which communicates with any suitable source of compressed air supply. The pipe 38 extends upwardly through the extension 39 of the turbine cylinder 34. The 85 chamber 37 is formed by the bearing housing 40 and extension 39.

The extension 39 forms a trunnion for the cylinder 34 and extends through a main cylinder 41, which latter is externally threaded as shown in Figure 1. The trunnion 39 is surrounded by a graduated dial 42 keyed thereon and also provided with the hand-wheel 43 also keyed thereto so as to permit rotation of the entire assembly within the 95 outer spindle 41 and thereby throw or move the grinding wheel in and out to conform to cylinders of different diameters. As the 100 rotor 32 (to the spindle whereof grinder 30 is secured) is mounted eccentrically in the turbine cylinder 34, it is evident that rotation of the entire turbine assembly, by rotation of hand-wheel 43, will cause the grinder wheel 30 to be moved through an eccentric and thus bring the grinding wheel 30 against the 105 walls of the cylinder to be ground.

The air entering through ports 36 into cylinder or tubing 34 impinges against the blades 33 (the latter being, by centrifugal force moved outwardly into contact with the inner wall of the tube 34) causes the rotor 32 to be revolved; the air being permitted to escape through outlet ports 44. The bearing housing 40 contains a race-way for the ball-bearings, indicated at 45, for the trunnion of 115 the rotor 32 and also provides a closure for the end of the cylinder or tubing 34. The bearing housing 40 is bored eccentrically as shown in Figure 2 so as to hold the rotor 32 in the eccentric relation previously described. The tube 34 at the lower end is also provided with a bearing housing 46 which likewise is eccentrically bored to receive the spindle 31 of the rotor and also to receive the ball-bearings shown at 47 and 47*, and 125 to maintain rotor 32 in the eccentric position relative to the interior of tubing 34. In order to take up all freedom in the bearings, I provide a compression spring 48, which bears at the lower end against the inner 130

- race-way of ball-bearing 47^a (which is immovably held in place) and exerts upward pressure against the ball-bearing race-way 47, which in turn bears against the lower 5 end of the rotor 32 which latter, therefore, exerts upward pressure against the ball-bearing race-ways 45 and as a result an automatic take-up for all freedom and wear in the bearings is provided.
- 10 Hand-crank 49 has a gear 50 keyed there-to which is in mesh with a gear 51 which is threaded onto the threaded cylinder or outer main spindle 41. Rotation of handle 49 and therefore of pinion 50 will rotate gear 51 15 and by reason of its threaded relation with spindle 41 causes the latter to travel either upwardly or downwardly, depending, upon the direction of rotation of handle 49. The object of this arrangement is to provide a 20 quick return movement of the grinding wheel after it has reached the maximum point of its downward stroke. This feature or operation also is used for truing the grinding wheel with a diamond when necessary. 25 The lower end of crank 49 is shown reduced and passes through the pinion 50 and also through a pinion 52 which in turn meshes with a gear 53 which has sliding or feathered relation with the cylinder or outer 30 main spindle 41.
- The ratio between pinion 52 and gear 53 is 2-to-1, whereas the ratio between pinion 50 and gear 51 is slightly greater than 2-to-1, in order that a desired feed of the main spindle 41 may be had. The pinion 52 is provided with a hub or extension 54, which extends through the extension of the main casing or housing; the lower end of the hub being threaded to receive a nut 55 on which 40 a handle 56 is trunnioned in any suitable manner. The lower end of the crank 49 extends through the hub 54 of pinion 52 and has a stop-nut 57 fixedly secured thereto by means of pin 58. The distance between the 45 lower surface of the casing extension and the stop-nut 57 is slightly greater than the thickness of nut 55 so that the latter may have slight travel lengthwise of the hub 54 of pinion 52. As is apparent from the 50 construction shown, when nut 55 is rotated by means of handle 56 so as to screw the nut 55 up against the bottom surface of the casing extension, pinion 52 will be locked against rotation and the pinion 52 in turn locks gear 53 and prevents its rotation, which results in preventing rotation of main spindle 41. If the crank 49 is rotated under these conditions, pinion 50 will rotate gear 51 and cause the main spindle 41 to travel 55 upwardly or downwardly depending upon the direction of rotation of crank 49; always moving the spindle 41 a distance equal to the pitch of the thread on spindle 41, thus serving as a quick return or quick longitudinal movement of the main spindle and the
- grinding wheel. On the other hand, if nut 55 is screwed in the opposite direction, by means of handle 56, so as to bring nut 55 into contact with lock-nut 57, it is evident that pinion 52 will be forced upwardly into 70 firm contact or clamping relation with pinion 50, so that pinion 52 will of necessity rotate with pinion 50. With this condition, rotation of crank 49 will not only induce main spindle 41 to be fed downwardly 75 (through the medium of pinion 50 and gear 51), but will also cause the main spindle 41 to be rotated, induced through rotation of pinion 52 and gear 53.
- This causes main spindle 41 to revolve 80 (through the medium of pinion 52 and gear 53) and while this is taking place gear 51, due to the difference in the number of teeth, will induce a gaining or losing effect; this gain or loss will act on the screw-threads 85 of main spindle 41 and cause the main spindle 41 to be fed upwardly or downwardly according to the differential action and the direction of operation of crank 49.
- In order to protect the main spindle 41 90 at its upper threaded end, I have shown a telescopic housing comprising a plurality of different sized sections 59, each having in-turned flanges at top and out-turned flanges at bottom so as to interlock; the top section 95 being secured to the spindle-head 60, while the lower section is immovably secured to the main casing cover 61. As is apparent, the sections 59 will be caused to collapse or telescope into each other as the main spindle 41 100 travels downwardly on its feed stroke; the sections expanding as the spindle 41 is returned upwardly.
- I also provide the lower end of the spindle 41 with a suitable dust guard, which is 105 preferably in the nature of suitable fabric or leather arranged in bellows-folds as shown at 62; one end whereof is secured to the main casing 27 in any suitable manner, as for example by means of suitable concentric rings as at 63 which are forced into the counterbore of housing 27; while the other end is secured to a ring 64 which is free to rotate on the lower end of the main spindle 41 in order that the ring 64 with the dust-guard element 62 will not rotate with the main spindle 41, but on the other hand be caused to fold or be extended, depending on direction of travel of the spindle, with the result that the lower end of operating spindle 110 during operation is enclosed and protected and ingress of dust or other foreign matter prevented.
- The air exhausting from rotor or turbine cylinder 34 through exhaust ports 44, enters 125 the main spindle 41 and acts as a cooling medium for the turbine assembly; and this exhaust air in turn is permitted to exhaust from the main spindle 41 through the exhaust ports shown at 65, which are prefer- 130

4
ably arranged in a suitable closure bushing or member at the lower end of the main spindle. With this arrangement, the exhausting air will also blow the ground particles out of the cylinder away from the operating point; the bushing with ports 65 at the same time serving to hold the motor assembly eccentrically in the main spindle 41; while the upper end of the motor assembly 10 is likewise held eccentrically in the main spindle 41 by means of a bushing 66. The bushings as stated maintain the motor assembly eccentrically in main spindle 41, while the motor, of course, is driven by the admitted compressed air; but as the main spindle 41 rotates through operation of hand-crank 49, it is apparent that the motor assembly is caused to move through an orbit, bringing the grinding wheel 30 successively into contact with the entire interior surface of the cylinder to be ground. The bushings which hold the motor eccentrically in the spindle 41 permit the motor assembly to be thrown into and out of operative contact with the 20 inner walls of the cylinder to be ground through proper rotation of hand-wheel 43.

For example, with the dial 42 set or rotated to zero, the grinder wheel 30 will be approximately at the longitudinal center or 30 axis of the assembled device and will merely describe a small orbit when the rotor is put into operation; on the other hand, when hand-wheel 43 is turned so as to move dial 42 to 180 degrees, the grinder-wheel 30 is moved 35 out from center and into contact with one side of the cylinder wall and when the rotor is in operation, the grinder wheel 30 will not only spin or rotate but will also be caused to travel through an orbit defined by the cylinder interior.

With this arrangement, adjustment of the grinder wheel 30, relative to the inner wall of the cylinder, when the wheel becomes worn, is permitted.

45 The compressed air line 38 is provided with a sleeve 67 which is provided with a valve 68 which seats at the lower end of housing 69, arranged in the extension 39 of cylinder or tube 34, and prevents the egress 50 of air upwardly through the upper end of the device; air pressure being below valve 68 maintains it on its seat. The lower end of the sleeve 67 is shown provided with an air strainer 70. As the air-line 38 must have 55 movement with the main spindle, I provide a yielding support for the air-line 38 in the form of a yoke or strap member 71, which is secured on the housing extension or hub and beneath a flange 72 on the hand-crank 49.

As shown in Figure 1, the exhaust ports 44 are preferably arranged in the V-shape formation so as to permit of sufficient exhaust and to prevent back pressure in front 65 of the blades 33 and therefore prevent back

pressure against the rotation of the rotor 32, as such pressure would diminish power on the opposite sides of the blades and reduce the driving power of the rotor.

The rotor 32 is provided with a passage 70 extending entirely therethrough as well as through its spindle 31, as shown at 73, see Figure 2, for the purpose of permitting introduction of grease, which may be done by the use of a well known grease gun; the 75 grease being introduced through the lower end of the passage 73 upon removing the retaining screw 73 (which retains the grinding wheel 30 on the end of the spindle 31); the grease passing up through passage 73 80 and thence out through the ports 74 provided in the spindles of the rotor and in the collars 75, 75 arranged above and below the rotor; thus allowing the grease to fill the 85 cavities about the collars 75 and to pass into the ball bearing raceways 45 and 47 at both ends of the rotor. The collars 75, 75 not only serve as thrust collars for the ends of the rotor, but also provide closures for the 90 ends of the slots in the rotor in which the blades 33 are mounted.

By providing the ports 65 in the bushing at the lower end of the main spindle or cylinder 41, the air, exhausting through ports 44 from the inner cylinder or spindle 34, is directed downwardly toward the grinder wheel and the exhaust air thus employed for blowing the ground material from the grinding wheel and thus prevents what is termed as "loading"; that is to say, the material is prevented from entering the pores of the grinding wheel, as filling of the grinding wheel with particles of metal would cause the latter to "burn". In the lower end of the main housing, the openings 29 enable constant inspection of the work being done; and the telescopic housing at the upper end of the main spindle 41 and the bellows-folds 62 at the lower end of the spindle provide protection for the spindle and prevent particles of metal or other foreign matter becoming lodged on the main spindle and thus interfering with its proper longitudinal and rotatable movements.

115 My invention provides a light portable grinder which is highly sensitive and whereby true accurate grinding of a cylindrical surface may be obtained in a minimum amount of time; truing of the cylinder being 120 accomplished without appreciably enlarging the bore because the grinder removes the least amount of stock and as a result the life of the triple valve, for which my grinder is especially adapted, is greatly enhanced. 125 With my improved precision grinder, as required in air-brake work, the use of high priced machine tools is eliminated; the truing operations at various points on a railroad system being possible, while at the same time the necessity for skilled operators is ob- 130

viated as the proper setting or truing location of the grinder is all automatically or mechanically accomplished, any wear in the bearings for the rotor portion of the grinder being automatically taken care of by the means hereinbefore described, so that possibility of vibration or chatter is eliminated.

The second or inner cylinder 34 is eccentrically mounted in the main cylinder 41 by means of the bushings at the upper and lower ends thereof; and the rotor 32 is eccentrically mounted in the second cylinder by means of the bearing housings 40 and 46 which are immovably secured within the second cylinder. The housing 46 just referred to is provided at its lower end with a grease retaining element 76 which is held in place by means of the collar 77 secured in the lower end of the housing 46 of inner cylinder 34; and the main housing 27 is preferably provided with suitable bushing as at 78 to receive the main cylinder 41. With the inner cylinder 34 and the rotor eccentrically mounted as shown, it is apparent that the grinding wheel 30, when the device has been adjusted so as to bring the grinding wheel into contact with the wall of the cylinder or valve to be ground, will, in addition to its rotation about its own axis, move through an orbit and therefore into contact with the entire inner wall of the cylinder or valve operated on; the operation being visible through the openings 29 in the base of the main housing.

I have shown what I believe to be a simple exemplification of the invention, which is especially adapted for precision grinding as required in connection with the triple valves employed in air-brake equipment and have described the same in terms employed merely as terms of description and not as terms of limitation, as structural modifications are possible and may be made without, however, departing from the spirit of my invention.

What I claim is:—

1. A grinder of the character described, comprising a main housing, a main cylinder longitudinally and rotatably movable in said housing, said cylinder being externally threaded, a second cylinder mounted in the main cylinder, closure means for the ends of the main cylinder whereby the position of the second cylinder relative to the longitudinal axis of the main cylinder is maintained, means whereby said position of the second cylinder may be regulated, intermeshing gear mechanism operatively connected with said main cylinder with a portion of said gear mechanism slidably connected to said second cylinder, whereby either longitudinal movement or longitudinal and rotatable movement of said cylinder may be obtained, and means for controlling said gear mechanism.

2. A grinder of the character described,

comprising a main housing provided with an extension or hub on one side thereof, a main cylinder longitudinally and rotatably movable in said housing, said cylinder being externally threaded, a second cylinder mounted in said main cylinder to move with said main cylinder, closure members for the ends of the main cylinder whereby the second mentioned cylinder is eccentrically held in the main cylinder, means whereby the position of the second mentioned cylinder within the main cylinder relative to the axis of the latter may be regulated, intermeshing gear mechanism operatively connected with said main cylinder with one portion of the mechanism having a slideable operative relation with said cylinder whereby either longitudinal movement or longitudinal and rotatable movement of said cylinder may be obtained, means for locking a portion of said gear mechanism against rotation, and means, mounted in the housing extension or hub whereby said gear mechanism may be rotated.

3. A grinder of the character described, comprising a main housing provided with openings in the side walls adjacent the lower end thereof, a main cylinder longitudinally and rotatably movable in said housing, said cylinder being externally threaded at its upper end, a second cylinder eccentrically mounted in said main cylinder, closure means for the ends of the main cylinder whereby the second mentioned cylinder is eccentrically held within the main cylinder, means secured to the upper ends of the cylinders whereby the position of the second cylinder relative to the axis of the first mentioned cylinder may be controlled, gear mechanism for controlling the first cylinder consisting of two pairs of intermeshing gears arranged in parallel relation one pair above the other, the ratio of one pair of intermeshing gears being somewhat greater than the ratio of the other pair of meshing gears, the gear of one pair having threaded relation with the threaded portion of the main cylinder while one of the gears of the second pair has a feathered relation with said main cylinder, means whereby said gears may be rotated, and means whereby a gear of one of said pair of gears may be placed into operative relation with a gear of the other pair or be locked against rotative movement.

4. A grinder of the character described, comprising a main housing, a main cylinder longitudinally and rotatably movable in said housing, said cylinder being externally threaded at its upper end, a second cylinder eccentrically mounted in the first mentioned cylinder and provided with a spindle disposed through the upper end of the first cylinder, closure means for the ends of the first cylinder whereby the second cylinder is eccentrically held in place, means secured

to the spindle of the second cylinder whereby its position in the first cylinder may be controlled, gear mechanism mounted in said housing and arranged in pairs, a gear of one pair having threaded relation with the main cylinder while a gear of the second pair has feathered relation with said cylinder, a hand-crank for operating the other gear of each pair, means whereby said other gear of one pair may be locked to a gear of the other pair so as to rotate therewith or to be locked against rotation, telescopic means intermediate of the housing and the upper end of the main cylinder for enclosing the latter, yieldable enclosing means secured to said housing and to the lower end of the main cylinder.

5. In a grinder of the character described, a main housing provided with a hub extension at one side thereof, a main cylinder externally threaded and longitudinally and rotatably movable in said housing, a second cylinder mounted in the main cylinder, two pairs of intermeshing gears arranged one above the other, the gear of one pair having threaded relation with said main cylinder, while the gear of the other pair has feathered relation with said cylinder, a hand-crank rotatably mounted in the hub extension of said housing with a gear of one of said pair of gears keyed thereto while a gear of the second pair is loosely mounted thereon, and clamping means secured to the lower end of said loosely mounted gear whereby said last mentioned gear may be clamped to the gear keyed to said hand-crank to rotate therewith or locked to said housing against rotation.

6. In a grinder of the character described, a main housing, a main cylinder externally threaded and longitudinally and rotatably movable in the housing, a second cylinder eccentrically mounted within the main cylinder, means for controlling the position of the second cylinder in said main cylinder, two pairs of intermeshing gears arranged one above the other, the gear of one pair having threaded relation with the threaded portion of the main cylinder while a gear of the second pair is feathered on said cylinder, a hand-crank mounted in said housing with a gear of one pair keyed thereto while the gear of the other pair is loosely mounted thereon and is provided with an extension or hub disposed through the housing, a clamping nut threaded on the extension or hub of said gear, an operating handle swiveled on said clamping nut, and a stop-nut secured to the

lower end of said hand-crank and beneath said clamping nut.

7. In a grinder of the character described, a main housing provided with a base portion having an external taper, a main cylinder externally threaded and longitudinally and rotatably movable in the housing, a second cylinder eccentrically mounted in the main cylinder and provided with a spindle disposed through the upper end of the main cylinder, closure means for the ends of the main cylinder whereby the second cylinder is eccentrically held in place, means disposed at the upper end of the main cylinder whereby the position of the second cylinder within the main cylinder may be controlled, a plurality of gears mounted in the housing, one of the gears having threaded relation with the threaded portion of the main cylinder while a second gear has feathered relation with said cylinder, a hand-crank, rotatably mounted in the housing, to which a third gear is keyed while a fourth gear is loosely mounted thereon, clamping mechanism operatively secured to the last mentioned gear whereby said gear may be made to rotate with the third mentioned gear or be locked against rotation, collapsible means secured to the housing and to both ends of the main cylinder whereby the ends of the latter are enclosed.

8. In a grinder of the character described, an elongated housing having a lateral extension on one side, a cylindrical member slideable in said housing and externally threaded, two pairs of gears arranged one pair above the other, the ratio of the gears of one pair being greater than that of the gears of the other pair, the gear of one pair being threaded on the threaded portion of said cylindrical member, while a gear of the second pair is feathered on said cylindrical member, a hand-crank rotatably mounted in said lateral extension of the housing, the second gear of said first mentioned pair being keyed to said hand-crank while the second gear of the other pair is loosely mounted on said hand-crank, said last mentioned gear being provided with an extended hub disposed through the lateral extension of the housing and externally threaded, a stop-collar secured to the lower end of the hand-crank, a clamp-nut threaded on the threaded end of the extended hub of said last mentioned gear and adapted to abut against the housing or said stop collar, and an operating handle swiveled on said clamp-nut.

OWEN D. KINSEY.
